UNITED STATES PATENT OFFICE.

MICHAEL C. RYAN, OF PHOENIX, NEW YORK.

HINGE.

1,248,407.

Specification of Letters Patent. Patented Nov. 27, 1917.

Application filed May 24, 1915. Serial No. 30,099.

To all whom it may concern:

Be it known that I, MICHAEL C. RYAN, a citizen of the United States, residing at Phoenix, in the county of Oswego and State 5 of New York, have invented certain new and useful Improvements in Hinges, of which the following is a specification.

This invention relates to certain improvements in hinges and particularly to improvements in the hinge of my Patent No. 803,509, dated Oct. 31, 1905; and the objects and nature of my invention will be readily understood by those skilled in the art in the light of the following explanation of the 15 accompanying drawing illustrating what I now believe to be the preferred embodiment or mechanical expression of my invention.

The object of the invention is to increase the strength and wearing qualities of certain 20 portions of hinges of the type illustrated by my above mentioned patent, as well as to improve the same in other respects.

The invention consists in certain novel 25 features in construction and in formations, arrangements and combinations as more fully and particularly set forth and specified hereinafter.

Referring to the accompanying drawings: 30 Figure 1, is a plan of a blank from which the butt leaf or member of the hinge is struck up.

Fig. 2, is a plan view of said member of the hinge.

Fig. 3, is a longitudinal section through 35 both leaves of the hinge on a somewhat enlarged scale.

Fig. 4, is a plan view of the hinge.

Fig. 5, is an end elevation thereof.

The hinge consists of two loosely joined 40 leaves or members 1, 2, of which the butt leaf or member 1, is preferably composed of a piece of sheet metal of any desired form or contour having suitable holes or perforations to receive fastening means, and having its pintle end formed with slot 3, to provide the hinge cross bar or pintle 4, connected to the body of the hinge leaf by side bars 8.

The other leaf or member 2, is also composed of a piece of sheet metal of any suitable form or contour having perforations or holes to receive fastening means. One end 45 of the member 2, is passed around the pintle 4, and through slot 3, of the butt member and is bent or rolled into an approxi-

mately-cylindrical preferably-closed eye 5, of such diameter as to encircle and permit turning movement on said bar or pintle.

The member 1, is formed from a sheet 60 metal blank (Fig. 1) having the elongated tapered end, tongue or projection 6. This tongue is formed by cutting triangular pieces from the corners of one end of the blank so as to leave the end portions of the 65 side edges of the blank beveled or converging from points about in line with the longitudinal axis of the slot 3, of the completed hinge member to the end edge of the projection. 70

The pintle of the hinge is formed by doubling back the elongated beveled edge projection approximately on the fold line 7 (Fig. 1) to produce the upper portion 4', joined to the lower portion by the curved 75 portion 4'', forming the rounded outer longitudinal edge of the completed pintle, while the opposite edge of the pintle is cut with the usually parallel metal edges 4^a, 4^b. The edges 4^a, 4^b, are preferably spaced a distance apart 80 so that while the two ply pintle is approximately flattened so as not to completely fill and occupy the eye of the other hinge leaf and so as to be of maximum strength and rigidity by reason of the doubled formation 85 thereof, yet said pintle is also preferably hollow and hooked, U-shaped, or approximately semi-cylindrical in cross section. 90

The rolled back free end of the elongated beveled edge projection thus forms the 95 pintle with a scraping edge 4^a, bearing against the inner surface of the eye 5, and performing the important function of scraping the inner surface of said eye, when either leaf of the hinge is swung on the hinge 95 axis, to prevent the eye becoming united to the pintle by rust or ice. Those skilled in the art will readily appreciate the liability of hinges exposed to the weather to become locked or bound together or stiffened at the 100 joints between the leaves and to consequently break at said joints when force is applied to flex or swing the hinges on or at said joints. I avoid this difficulty by providing the hinge with the pintle whereby the hinge 105 joint is greatly strengthened, and furthermore, by providing the pintle with the free or scraping edges 4^a, 4^b, with an intervening space for the clearance of rust, ice or other foreign material, the hinge can clear 110 itself when the joint between the leaves become stiffened or locked, without danger

of breaking the leaves apart at the joint. Furthermore, by providing the pintle of an approximately semi-cylindrical or U-shaped form in cross section, the pintle can approximately fill say about one half of the eye and thereby reduce lateral play between the pintle and eye to the minimum.

While the hinge of my hereinbefore mentioned patent has been sold in large numbers and accomplished the desired results, yet in hinges intended for certain uses, the flat single ply pintle was weak at or near the ends of the surrounding eye particularly under excessive strain transversely thereof and the tendency of this pintle under certain circumstances to tear or break across at the ends of the slot was increased by the square or angular ends of the cut forming the slot with right angular outer corners.

In the hinge of the patent where employed for certain purposes, the said pintle constituted the point of greatest weakness, the pintle would break before the metal of the hinge eye would bend sufficiently to open said eye.

The pintle when doubled back according to my present invention to form two plies, whether said plies are left separated or brought approximately together, is so strengthened that the hinge eye becomes the point of weakness in the hinge. I accomplish desirable results by folding back the end of the blank projecting beyond the slot to form the two-ply pintle which strengthens the pintle against breaking across at or near its end portions, and also brace and strengthen the pintle against transverse fracture or tearing at its end portions by providing the slot with curved or rounded ends, particularly at the outer corners thereof, thereby increasing the amount of metal at the ends of the pintle and avoiding angular slot corners which tend to weaken the metal at such points and to facilitate the starting of tears or fractures.

While in the specific example illustrated, I show the pintle plies, and their edges 4^a, 4^b, definitely spaced apart to provide a hollow open side pintle whereby an advantageous species is provided yet I do not wish to limit the general features of my invention to the spacing between said plies and edges, or whether said plies are definitely spaced or approximately brought together.

The leaf 2, passes beneath the pintle and up through the slot and then turns outwardly over the pintle and is closed down against the body of its leaf 2, outwardly beyond the pintle so that the eye presents an approximately smooth or seamless inner surface for engagement with the pintle. The width of the eye 5, is approximately equal to the length of the slot 3, and hence the leaf 1, projects laterally in opposite directions beyond the ends of the eye. It is ob-

jectionable to leave outwardly projecting shoulders, ends or corners (such as formed by eye and pintle ends) unguarded inasmuch as such projections are liable to catch and tear or otherwise damage fabrics, furniture, wood work, or even the hands or other parts of the person. I avoid abrupt shoulders at the ends of the pintle 4, and furthermore, I guard the end edges of the eye 5, by beveling or tapering the side edges of the projection 6, of the blank from which leaf 1, is bent up so that the straight longitudinal edge of the superimposed ply of the pintle does not appreciably extend beyond the ends of the eye 5, and the ends of said superimposed ply gradually taper off and merge into the side edges of the body of the leaf 1, and form beveled or inclined guard edges 9, that serve to guard the ends of the eye and deflect objects from direct engagement therewith.

This result and formation is attained by bending up the tapered-edge outer end of the projection 6, to form the pintle, and in this connection the pintle guard edges preferably start at points on the side edges of the butt leaf about in line with the longitudinal axis of the slot. However, I do not wish to limit all features of my invention to the provision of beveled guarding edges at the ends of the pintle although I consider this a valuable and important feature in hinges of this general type.

As to this beveled guarding edge feature of my invention, I am not limited to hinges having the particular form of pintle herein shown and described.

It is evident that various departures might be resorted to without avoiding the spirit and scope of my invention and hence I do not wish to limit myself to the exact disclosure hereof.

What I claim is:—

1. A hinge consisting of a leaf having a transverse slot closed at the ends and located near an end of the leaf, said end of the leaf being tapered, a portion of the end of the leaf beyond said slot being turned back toward said slot to provide a doubled pintle having beveled edges forming its projecting ends, and another leaf having an eye loosely passing through said slot and surrounding said pintle, said ends of the pintle extending beyond the ends of said eye.

2. A hinge consisting essentially of a leaf having a slot near one end, said end of the leaf being folded back to form a double pintle parallel with and forming one wall of the slot, the ends of said pintle being beveled to constitute guard forming edges substantially as described, the edges of the leaf at the ends of the slot being beveled approximately in continuation of said beveled ends of the pintle, and another leaf having an eye encircling said pintle, said beveled ends

of the pintle extending beyond the ends of the eye.

3. A hinge consisting of a leaf having a transverse slot closed at its ends and formed with curved outer corners, the end of the leaf beyond said slot being tapered and doubled back toward said slot to form a pintle with beveled end edges opposite said curved corners of the slot, and another leaf

having an eye extending through said slot 10 and embracing said pintle, substantially as described.

In testimony whereof I affix my signature in the presence of two witnesses.

MICHAEL C. RYAN.
